US00D918237S

(12) **United States Design Patent** (10) **Patent No.:** **US D918,237 S**
Lee (45) **Date of Patent:** **** May 4, 2021**

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventor: **Kyuho Lee**, Seoul (KR)

(73) Assignee: **SAMSUNG ELECTRONICS CO., LTD.**, Suwon-si (KR)

(**) Term: **15 Years**

(21) Appl. No.: **29/689,733**

(22) Filed: **May 1, 2019**

Related U.S. Application Data

(63) Continuation of application No. 29/590,742, filed on Jan. 12, 2017, now Pat. No. Des. 849,765.

(30) **Foreign Application Priority Data**

Jul. 29, 2016 (KR) 30-2016-0037219
(51) **LOC (13) Cl.** **14-04**

(57) **CLAIM**

The ornamental design for a display screen or portion thereof with graphical user interface, as shown and described.

DESCRIPTION

FIG. 1 is a front view of a display screen or portion thereof with graphical user interface showing my new design according to a first embodiment; and,

FIG. 2 is a front view of a display screen or portion thereof with graphical user interface showing my new design according to a second embodiment.

The broken lines at the outer perimeter in the drawings depict a display screen or portion thereof and form no part of the claimed design. The remaining broken lines in the drawings depict portions of the graphical user interface that form no part of the claimed design.

1 Claim, 2 Drawing Sheets
